UNITED STATES PATENT OFFICE.

SIMEON V. TRENT, OF SALT LAKE CITY, UTAH.

CELLULAR DIRIGIBLE AIRSHIP.

Application filed March 31, 1921. Serial No. 457,227.

To all whom it may concern:

Be it known that I, SIMEON V. TRENT, a citizen of the United States, residing at Salt Lake City, in the county of Salt Lake and State of Utah, have invented new and useful Improvements in Cellular Dirigible Airships, of which the following is a specification.

My invention relates generally to air craft, and more particularly to that type of airship having an elongated cellular body, the framework of which is substantially rigid and the cells or chambers within the body structure being provided with containers for gas that is utilized as the lifting medium and containers for air that is utilized as ballast.

The principal objects of my invention are, to generally improve upon and simplify the construction of the existing forms of air craft of the particular type to which my invention relates, to provide an improved form of skeleton framework for air craft, said framework being of the rigid structure type, thereby materially increasing the strength and stability of the craft and consequently increasing the factor of safety in operation, and, at the same time, materially decreasing weight and minimizing the cost of construction.

Further objects of my invention are, to provide an improved form of airship framework wherein all the principal stresses are concentrated upon a centrally arranged longitudinally extending box girder that is particularly designed for the effective resistance of all compression and tensile stresses, and which includes a pair of substantially parallel trusses rigidly connected to each other and said trusses having depending integral portions that serve as a framework for supporting the operating and controlling mechanism of the airship, to provide in the skeleton framework a series of compartments or chambers that are adapted to receive gas containers and which latter correspond in form and size with the chambers or compartments, thereby utilizing practically all the space within the cellular body, to provide relatively simple and efficient means in the form of non-combustible partitions that are disposed between the gas container com-

partments so as to bulkhead each gas container from the next adjacent containers, to provide within the framework a plurality of sets of centrally arranged containers for air or gas, thereby providing for additional gas capacity or for air ballast, to provide means for controlling the air ballast so as to quickly and accurately change or shift the position of the body of the ship through a vertical plane so as to control the "trim" of the ship and to cause the same to ascend or descend during forward flight, to construct the air containers in the form of self-deflating bags with the inlet and outlet openings in the bottoms thereof in order that said bags or containers may readily expel the air that has been forced into them for ballast, to provide an airship wherein the hull or body structure is given stream line form as a result of uniform contraction of the cross-sectional area of the body from bow to stern, and further, to provide an airship hull having semi-circular sides and with flattened top and bottom, thus producing a hull or body having the form of an oblate spheroid in cross section, and which form reduces the vertical dimension of the body and relatively increases its breadth or beam.

A further object of my invention is to provide relatively simple and efficient means for controlling the airship while the same is ascending, while in flight and while descending and landing.

With the foregoing and other objects in view, my invention consists in certain new and novel features of construction and arrangement of parts that will be hereinafter more fully described and claimed, and illustrated in the accompanying drawings, in which—

Fig. 1 is a top plan view of an airship of my improved construction.

Fig. 2 is a horizontal section taken lengthwise through the center of the body of the airship.

Fig. 3 is a side elevational view of the airship.

Fig. 4 is an enlarged cross section taken approximately on the line 4—4 of Fig. 3.

Fig. 5 is a horizontal section taken approximately on the line 5—5 of Fig. 4.

Fig. 6 is a side elevational view of one of

the twin trusses of the box girder that forms the main longitudinal member of the framework of the airship.

Fig. 7 is a cross sectional view taken approximately through the center of the skeleton framework of my improved airship.

Fig. 8 is a diagrammatic view of the banks or sets of air and gas containers that are utilized in the cellular frame of my improved airship, and also showing the pumps that are utilized for handling the air and gas in said containers.

Fig. 9 is a side elevational view of one of the joints utilized for connecting the tubular members of the framework of the airship.

Fig. 10 is a top plan view of the joint.

Fig. 11 is a horizontal section taken approximately on the line 11-11 of Fig. 9.

Fig. 12 is a plan view partly in section of a modified form of the joint.

Fig. 13 is a cross-sectional view taken on the line 13-13 of Fig. 12.

In the construction of the frame of my improved airship, I make use of a centrally arranged longitudinally disposed box girder that is of skeleton construction and which forms the "backbone" or main member of the entire structure, and said main frame member or box girder comprises a pair of vertically disposed longitudinally extending trusses, one of which is illustrated in Fig. 6.

Each truss is composed of a plurality of longitudinally extending members 10, preferably spaced at equal distances apart, a series of vertically disposed members 11 certain of which, at the center of the truss, are extended downwardly as designated by 11^a, and these downwardly extending vertical members combine with longitudinally disposed members 10^a in forming an integral depending framework that cooperates with the corresponding depending framework of the companion truss in forming a skeleton structure for the support of the operating and control mechanism.

The members 10 and 11 at the forward end of each truss structure are arranged so as to produce a pointed forward end such as 12.

The longitudinal members 10 and 10^a of each truss and the vertical members 11 and 11^a, are preferably formed of metal tubing in sections, and the adjacent ends of the sections are rigidly connected in any desired manner, but preferably by means of an improved joint structure that I have devised and which is illustrated in Figs. 9 to 13, inclusive. This joint member, which, as a whole, will be designated by the numeral 13, includes an internal member or bushing 14 that corresponds in shape to that of the completed joint, and the legs or projections of this internal member are formed so that

they will snugly fit in the end portions of the tubular frame members that are to be united.

Applied to the end portions of the frame members or those portions that inclose the internal member or bushing, is a sectional or divided member, preferably a pair of plates such as 15 and which are provided on their inner faces with seats 16 which snugly receive the end portions of the frame members.

The plates or members 15 are rigidly secured to each other in any suitable manner, preferably by means of screws or bolts such as 17 and said plates being perforated as designated by 18 in order to receive the end portions of stays or reinforced members such as tie wires or braces.

In order to firmly secure the frame members, the internal member or bushing and the inclosing members, to each other, pins such as 19 are inserted through said inclosing members, the frame members and the portions of the legs or projections of the internal member or bushing.

By virtue of the construction just described, a very strong and substantial joint is produced between the adjacent ends of the members that make up the trusses and side portions of the frame of my improved airship, and which joint structure is relatively strong without material increase in weight.

In the modified form of joint structure illustrated in Figs. 12 and 13, a short tubular joint member such as 20 has its end portions 21 reduced in diameter, and these reduced portions are seated in the adjacent ends of a pair of the frame members, and enclosing the ends of the frame members and the inserted ends of the joint members, are clamping bands 23, each of which is preferably made in two parts that are joined together to clamp the engaged frame member and joint member by means of screws or bolts such as 24.

The projecting end portions of the clamp members are provided with apertures 25 that are adapted to receive tie members or braces. To rigidly secure the parts of this form of joint member to each other, pins such as 26 are inserted through the end portions of the frame members, through the clamping members 23 and through the inserted end portions 21 of the tubular joint member.

To reinforce each truss member of the framework, intermediate ties or braces such as 27 are disposed between the vertical members 11 and connected to the longitudinally disposed members 10, and a further reinforcement is provided by arranging diagonally disposed tie wires or braces such as 28 between the joint members 13 that connect the members 10 and 11, and this same

reinforcing and strengthening arrangement is carried out in the depending portion of each truss, and which includes the parts 10^a and 11^a.

- 5 The two trusses thus constructed are arranged so that the space between them gradually decreases in width toward their rear ends, and said trusses are rigidly secured to each other by suitably arranged transverse tie members 29, the ends thereof being secured to the truss forming members by joint structures 13, as described, and these transverse tie members being preferably spaced at equal distances apart throughout the 10 lengths of the trusses and the spaces between said tie members forming substantially rectangular pockets or chambers 30 that are adapted to be occupied by collapsible containers that may be filled with air to serve 15 as ballast while the airship is in operation.

The pair of trusses constructed as just described and tied together throughout their lengths by the members 29 constitutes a box girder, and as the same is centrally arranged 20 and extends lengthwise of the completed structure, it forms a strong and rigid backbone or skeleton framework that is effective in resisting all compression and tensile 25 stresses that may be deflected while the airship is in service.

The ends of vertically disposed semi-circular ribs 31, preferably formed of metal tubing, are connected by joint members 13 to the upper and lowermost members 10 of 30 each truss, and these ribs are preferably located in transverse alignment with the tie members 29.

Each rib 31 is connected at intermediate 40 points by horizontally disposed braces or tie members such as 32 to the corresponding vertical members 11 of the adjacent truss, and the intermediate portions of said braces or members 32 are connected by vertical ties or braces 33 and the ends of which latter 45 are connected to the ribs 31.

Members 32 and 33 are connected to each other, to the ribs 31 and to the truss forming members, by the hereinbefore described joint members 13, and said joint members are 50 preferably tied to each other by suitable diagonal braces or tie wires such as 34.

Secured to ribs 31 preferably by joint members such as 13, are longitudinally disposed frame members 35, preferably formed 55 of metal tubing, the same extending the entire length of the trusses forming the centrally arranged box girder and the forward ends of these longitudinally extending members are suitably connected to the parts 60 of the frame that form the pointed forward ends 12 of said trusses.

The spaces 36 between the centrally arranged box girder and the ribs 31 and the transverse skeleton structures comprising the members 32 and 33, form vertically dis-

posed semi-circular pockets or compartments that are adapted to be occupied by correspondingly shaped gas containers; and in order to properly support the walls of said gas containers, each pocket or chamber 70 36 is inclosed by wall structures 37, the same being preferably formed of reticulated material such as wire netting combined with sheets of asbestos or like fireproof material.

Thus, practically the entire space between the sides of the box girder and the ribs 31 and longitudinally disposed members 35, is divided into a series of gas bag chambers or pockets and the latter are provided with fireproof walls that serve to protect the bags 80 positioned in said pockets, and likewise, to effectually isolate said bags from each other in the event of fire in any one pocket or compartment.

The reinforced fireproof walls 37 are preferably tied by means of wires to the adjacent members of the framework, and such construction serves to materially reinforce and stiffen said framework.

Arranged in each compartment 36 and within the reinforced fireproof walls inclosing the same, is a vertically disposed semi-circular container 38 that is preferably formed of rubberized fabric or flexible material that will contain gas and the lower end of each bag or container is provided with a tubular member 39 that projects horizontally outward into the lower portion of the space between the trusses of the box girder, and said tubular members serving as 100 an inlet and outlet for the gas that is delivered to and withdrawn from the container.

Secured to the external surface of the collapsible bag or container are suitable lacings 40 that are extended through suitably located openings in the reinforced fireproof walls 37, and said lacings being tied to adjacent parts of the framework of the structure in order to maintain the bag or container in distended position.

By releasing the lacings that connect the upper portion of the bag to the adjacent framework, said upper portion will, when the valve controlling outlet 39 is opened, 115 collapse or move downwardly into the lower portion of the bag, thereby effecting a discharge of practically all the gas contained therein.

The entire series of gas bags or containers 38 are divided into two or more sets of banks, and in Fig. 8 I have shown said bags or containers divided into three banks or sets, A, B and C, such arrangement being 120 carried out in order to more readily control the disposition of the entire volume of gas utilized for lifting and sustaining the airship, and, as illustrated, the tubular members 39 at the lower ends of all of the bags or containers are connected, by branch pipes 125 130

41, to a main gas supply pipe 42 and each branch pipe being provided with an ordinary stop or cut-off valve 43 and with a check valve 44.

- 5 Arranged in the lower portion of each pocket or chamber 30 within the box girder is a horizontally disposed plate or platform 45 upon which rests the lower end of a collapsible bag 46 that is formed of rubberized 65 fabric or analogous material and which is adapted to contain air under pressure and which is utilized as ballast for the airship. Each collapsible bag or container is provided at its corners with loops such as 47, 70 and the latter are arranged to slide freely upon guide rods 48 that project upwardly from the corners of said platform and the upper ends of said rods being supported in any suitable manner.
- 20 Arranged on top of each air bag or container 46 is a flat plate 49 that serves as a weight to fully collapse a bag when the vent at the bottom thereof is opened, and said weight is provided with perforated ears 50 75 that are arranged to slide upon the rods 48.

Leading from the lower end of each air bag or container is a tube 51, and the entire series of these tubes are connected to branch tubes 52, that, in turn, are connected to a secondary supply pipe 53, and which latter is connected to a primary supply pipe 54.

The entire series of air bags or containers is divided into two or more sets or banks, 35 as illustrated in Fig. 8, in order to more readily control the disposition of the entire volume of air taken into said bags as ballast.

Each pipe 52 is provided with an ordinary stop or cut-off valve 55, and supply 40 pipes 53 and 54 are provided with suitably located cut-off and check valves.

Gas supply pipe 42 and air supply pipe 54 are directly connected to each other, and by means of branch pipes 55, these pipes are 45 connected to a pair of fans or compressors 56. Leading to the latter is a supply pipe 57 that is adapted to conduct air or gas to either one of said fans or compressors. Two fans or compressors are provided in order to 50 have one in reserve in the event that the one under operation becomes broken or otherwise inoperative.

The fans or compressors may be driven in any suitable manner, preferably by motors 55 such as 58.

Pipes 42, 54, 55 and 57 are provided with suitably located check and stop valves to control the passage of air and gas through 60 said pipes.

Arranged between the depending portions of the trusses are horizontally disposed platforms 59 and which divide the space between said depending portions into chambers that are adapted to accommodate the

crew and passengers of the airship, as well 65 as the operating and control mechanisms, fuel and the like; and preferably located on the lowermost platform, are suitable motors (not shown) that are arranged to drive propellers 60 that are positioned at both ends 70 of the depending portion of the airship. (See Fig. 3.)

The entire depending structure of the airship just described may be suitably housed 75 in to form closed cabins, and the outer walls of the various compartments in said cabin structure may be provided with suitably located doors and windows.

Arranged beneath the depending cabin structure is a series of transversely disposed 80 axles 61 that carry relatively small heavy traction wheels 62, the same providing a rolling support for the airship while the latter is upon the ground.

Projecting laterally from the lower portions of the sides of the body of the airship are plane members 63 that may be slightly curved in cross section and which perform the functions of stabilizers to assist in maintaining equilibrium of the airship while the same is in flight. These plane members may be tied to the depending cabin structure by suitable braces or tie wires 64.

Hinged on horizontal axes to the underside of the body of the airship, in front and to the rear of the cabin structure, are planes 65 that may be utilized for guiding the airship vertically during its forward flight, and which plane members may be swung from one position to another in any suitable manner, preferably, by means of operating connections that extend into the cabin structure.

The rear portion 66 of the body of the airship is constructed in the form of a vertically disposed wedge, and arranged on the outer faces of this wedge-shaped portion, and preferably at a point midway between the top and bottom of the body structure, are horizontally disposed stabilizing planes 67.

Arranged on top and bottom of the rear portion of the body of the airship, are vertically disposed stabilizing planes 68, and mounted to swing upon a vertical axis 69 immediately to the rear of the wedge-shaped rear end of the body of the ship, is a vertically disposed rudder 70 that is operated from the cabin structure by suitable connections; (not shown).

One of the pockets or chambers 30 at the center of the body of the airship, and which is designated by 30^a, is not provided with one of the collapsible air ballast bags, and this particular chamber provides a passageway to permit members of the crew to readily ascend from the cabin structure to the top of the body of the airship, and dis-

posed about the upper end of this opening or passageway and secured to the upper portion of the framework of the ship, is a suitable railing 71.

5 The entire body portion of the airship is provided with a sheath or covering 72 and which latter may be of any suitable material, for instance, a relatively fine, light-weight fabric such as silk or linen and 10 which may be treated to render it water-proof and practically airproof.

To render my improved airship buoyant, pipe 57 is connected to a suitable source of gas supply, and either one of the fans or 15 compressors 56 is operated to draw gas from said source of supply and force it through pipes 55, 42 and 41 into the gas bags or containers 38. During this filling 20 operation, cut-off valve in pipe 54 must be closed and all of the stop or cut-off valves 25 43 in pipe 41 opened.

Thus all of the bags or containers 38 will be filled with gas, the total volume of which is considerably in excess of the amount required to lift the airship and its load.

If desired, one or more of the valves 43 may be closed during the gas filling operation, thereby cutting out the corresponding 30 bag or bags and leaving the same empty so as to be available to later receive a portion of the gas supply from the filled bags in event that the total volume of gas expands under change of temperature, and thus the 35 gas supply maintained on the ship can be conserved.

The necessary ballast for the ship is provided by filling the bags or containers 46 with air that is compressed to two or more atmospheres, said air being forced into said 40 bags by one of the fans or compressors 56 and through pipes 54, 53 and 52.

Obviously, when air is forced into the bags or containers, the gas connection to 45 pipe 57 must be removed in order to permit air to enter said pipe.

When deflated, the bags will be collapsed under the weight of members 49, and as the air is forced into said bags or containers, they will rise and expand within the pockets 50 or chambers 30 until they practically fill the same.

By arranging the air ballast bags or containers in sets or banks, as illustrated in Fig. 8, and providing an outlet valve such 55 as 55 for each set or bank, it is possible to manipulate the entire volume of air ballast so as to shift the weight of the same from one longitudinal point to another throughout the length of the airship and consequently 60 vary the inclination of the ship during its forward flight; and in the event that the air ballast is permitted to exhaust from any one or all of the banks or sets of containers, the collapsed and empty bags can

be readily refilled by operating the air pump 65 or compressor and properly manipulating the valves that are located in pipes 52, 53 and 54.

By locating the combined air outlet and inlet in the bottom of each bag or container 70 46 and arranging a weight on top of said bag, the complete discharge of air from said bag is insured, and while the bag is being deflated, it will be guided upwardly through its pocket or compartment by the loops 47 75 which traverse the rods 48.

During flight of the airship, the propellers 60 are operated to drive the ship forwardly, and during forward flight, the vertical and lateral movements of the ship are guided 80 by manipulation of the planes 65 and rudder 70.

By spacing the trusses of the box girder a substantial distance apart and making the frame portions of the body structure to the 85 sides of said trusses of true semi-circular shape in cross section, the entire body portion of the airship throughout its length, has the cross section of an oblate spheroid, and this particular form of the body is effective 90 in increasing its sustaining effect while in flight, and at the same time, minimizing wind resistance.

Inasmuch as the space between the trusses gradually decreases toward their rear ends, 95 the body of the airship is given a stream line effect throughout its length, and which particular formation is especially desirable in air craft of this type.

Obviously, minor changes in the size, form 100 and construction of the various parts of my improved airship may be made and substituted for those herein shown and described without departing from the spirit of my invention, the scope of which is set forth in 105 the appended claims.

I claim as my invention:

1. In an airship, a skeleton framework comprising a pair of trusses connected throughout their lengths to form a box girder, semi-circular ribs rigidly connected at both ends to the sides of said box girder, and the spaces between the trusses of the box girder and between said trusses and said 110 ribs being divided into pockets that are adapted to receive collapsible containers for gas and air.

2. In an airship of the rigid structure type, a skeleton framework of sectional constructions, the principal longitudinal member of which is of box girder construction, centrally located, and extending vertically to the full height of the hull and under-structure so as to divide the hull vertically 115 into two equal semi-circular sections and one central rectangular section, each semi-circular section being sub-divided into a series of equal semi-circular recesses, and 120 125

- the central section being sub-divided into a series of rectangular recesses.
3. In an airship, a skeleton framework of sectional construction, the main longitudinal member of which is in the form of a box girder, centrally located and extending vertically to the full height of the hull and understructure so as to divide the hull vertically into two equal semi-circular sections and one central rectangular section, each semi-circular section being subdivided into a series of semi-circular recesses and the central section into a series of rectangular recesses, said skeleton framework gradually decreasing in width toward its rear end whereby a streamline effect is produced in the completed structure.
4. In an airship, a skeleton framework of sectional construction whose main longitudinal member is a box girder centrally located and extending vertically to the full height of the hull and understructure, thereby dividing the hull into two semi-circular side sections suitably sub-divided for the reception of gas cells and a central and rectangular section specially adapted for receiving cells for air ballast and for surplus gas storage, said main box girder being diminished in width from front end to back end in order to attain a proper streamline for the entire length of the hull.
5. In an airship, a skeleton framework including a centrally arranged box girder, containers for air arranged within said box girder and containers for gas arranged in the skeleton framework to the sides of said box girder.
6. In an airship, a skeleton framework including a centrally arranged box girder, containers for air arranged within said box girder, containers for gas arranged in the skeleton framework to the sides of said box girder, and means for charging said containers with air and gas, respectively.
7. In an airship of the rigid structure type, a skeleton framework including a pair of longitudinally and vertically disposed converging trusses extending to the full height and length of the entire structure and rigidly connected to each other so as to form a box girder, integral extensions extending from said box girder for containing the operating and controlling mechanism of the airship, a series of vertical semi-circular ribs on each side of said box girder and rigidly attached to same and to each other, the whole forming two series of vertical semi-circular recesses in the side portions and a single series of rectangular recesses in the central portion.
8. The combination in an airship having a skeleton frame and adapted to rely exclusively upon air ballast, of air ballast means for operating said airship, which air ballast means includes collapsible containers that are external to the flotation gas containers and are arranged in separate and independent compartments in the framework of the airship, said containers being adapted to receive air to be utilized as ballast, means for forcing air under pressure into said containers, and means for controlling the admission of air into and the discharge of air from said containers.
9. In an airship adapted to rely exclusively upon air ballast, a collapsible air ballast container external to the containers for flotation gas and having its lower portion secured to parts of the airship, inlet and outlet connections for said container, and gravity means for effecting the collapse of said container when the air is released therefrom.
10. In an airship, an elongated framework in which is formed a centrally arranged row of pockets and rows of pockets to the sides of said centrally arranged row, self-deflating air ballast bags arranged in the central row of pockets, and gas containers arranged in the rows of pockets to the sides of said centrally arranged row.
11. In an airship, an elongated framework in which is formed a centrally arranged row of pockets and rows of pockets to the sides of said centrally arranged row, self-deflating air ballast bags arranged in the central row of pockets, gas containers arranged in the rows of pockets to the sides of said centrally arranged row, means for delivering air under pressure into said air ballast bags, and means for delivering gas into said gas containers.
12. In an airship, a framework composed of assembled sections of tubing, a bushing inserted in the adjacent ends of the tubular sections of said framework, and a split cap inclosing the adjacent ends of said tubular sections and the inserted bushing.
13. In an airship, a framework composed of assembled sections of tubing, a bushing inserted in the adjacent ends of a pair of the tubular sections of said framework, a split cap inclosing the adjacent ends of said tubular sections and the inserted bushing, and means for rigidly connecting the parts of the split cap to each other.
14. In an airship, a framework composed of assembled sections of tubing, a bushing inserted in the adjacent ends of a pair of the tubular sections of said framework, a split cap inclosing the adjacent ends of said tubular sections and the inserted bushing, and means for rigidly connecting the parts of the split cap, the tubular sections and the inserted bushing, to each other.
15. In an airship, a joint structure for substantially hollow frame members comprising an internal member corresponding in shape to that of the completed joint, portions of which member are inserted in the

end portions of the hollow members, and a divided member inclosing those portions of the hollow members that inclose parts of said internal member.

5 16. In an airship, a joint structure for substantially hollow frame members comprising an internal member corresponding in shape to that of the completed joint, portions of which member are inserted in the 10 end portions of the hollow members, a divided member inclosing those portions of the hollow members that inclose parts of said internal member, and dowell pins seated in said divided member, the hollow members 15 and said internal member.

17. In an airship of the rigid structure type, a skeleton framework including a pair of longitudinally and vertically disposed trusses extending to the full height and

length of the entire structure and rigidly 20 connected to each other so as to form a box girder, a series of vertical semi-circular ribs on each side of said box girder and rigidly connected to the same and to each other, the whole forming two series of vertical semi-circular recesses in the side portions and a single series of rectangular recesses in the central portion, the mentioned pair of main vertical trusses having substantially vertical extensions in continuation thereof for 25 containing the operating and controlling mechanisms and the cabins in a manner to assure the rigidity of the entire frame as a substantially integral structure.

In testimony whereof I have signed my 30 name to this specification.

S. V. TRENT.
